UNITED STATES PATENT OFFICE.

EDWARD J. ZIOCK, OF ROCKFORD, ILLINOIS.

APPARATUS FOR DRYING AND SHAPING KNITTED ARTICLES.

Original application filed May 7, 1924, Serial No. 711,565. Divided and this application filed September 20, 1924. Serial No. 738,755.

This invention relates in general to certain operations in the finishing of fabric or knitted articles after they have been manufactured and subjected to treatment by liquids. 5 For example, in the manufacture of hosiery my invention relates to drying and shaping socks or stockings after they have been manufactured and treated in any way by liquids. Such treatment may consist merely in wetting 10 out the socks or stockings or it may comprise the various operations included in bleaching, mercerizing, dyeing and related processes.

The present application is a division of my parent application Serial No. 711,565, 15 filed May 7th, 1924, which eventuated in Patent 1,623,080 issued April 5, 1927.

The primary purpose of the present invention is to provide a new apparatus for drying and shaping knitted articles, whereby such 20 operations may be performed more expeditiously and with a greater degree of uniformity than with prior apparatuses.

Another purpose of my invention is to provide improved means for drying and shaping 25 knitted articles which is especially suited to function in cooperation with apparatus of the character disclosed in said parent application which comprehends performing in one machine or apparatus substantially all of the 30 operations necessary for completely finishing a knitted article after the knitting thereof.

In furtherance of the foregoing my invention contemplates broadly, certain new methods, principles and apparatus coordinated so 35 as to perform in a single machine the many operations required in finishing stockings or other knitted articles, and doing in a comparatively short time, in fact a matter of minutes, what heretofore required in the commercial finishing of stockings in large quantities, many days from the time the stockings 40 entered a stock room where the lots were made up preparatory to entering upon the finishing operations, until the finished articles reached the shipping room.

While the present invention deals more particularly with the drying and shaping operations in combination with liquid treating operations in general, its relation to the 45 entire method will be better understood by considering first a brief description of what such method comprises. This method consists, generally stated, in completely finishing the knitted articles by a series of operations 50 performed in succession or progressively by

coordinated devices. These operations are all performed on each knitted article while it is boarded, that is, carried or held on a board or form which is preferably flat and shaped to conform substantially to the shape of the 60 article, and to hold the fabric extended to permanent dimensions. More particularly the method consists in boarding the stockings or other articles at a loading station, carrying the boarded stockings at uniformly spaced 65 intervals by means of an endless continuously traveling carrier successively to different stations at which the stockings are singed, wetted out, dyed, subjected to a scroupe bath, dried, shaped, and finally delivered to an inspection station and unloaded. 70 While the method described embraces practically all of the operations which might be performed in dyeing and finishing a conventional black stocking, it should be understood 75 that the method should not be confined to these particular steps or operations but might be practiced with fewer coordinating operations for accomplishing a unitary result. This method, the several steps of which are 80 explained more fully in said parent application, makes possible combining into a single machine, devices for performing in a new and better way certain operations which were heretofore performed by independent machines. The many advantages of this method 85 will be apparent to those skilled in this art when it is considered that under the prior practice the individual machines and devices were segregated, due to the nature of their 90 construction and operation making it necessary to handle and truck the stockings between each operation. This practice also imposed a comparatively high labor and operating cost and, moreover, made it necessary 95 to allow for each batch or lot of stockings a comparatively large surplus number of stockings in order to prevent delay due to losses occasioned by imperfections and roughing the stockings during certain operations, 100 and for other reasons well known in this art. It also required matching the stockings as to shades and length. These limitations imposed a considerable amount of time so that in some hosiery mills it required several weeks 105 or more for the passage of a stocking through the mill for finishing. According to my present invention the operations contemplated herein, that is, of subjecting the stockings to one or more liquid treatments and drying 110

and shaping them, are performed on a stocking while it is on a board or form and by employing an endless carrier for moving the boarded stockings from station to station at which novel devices are employed for performing the several operations. Thus the many manual operations heretofore required are eliminated and a more uniform product is produced in a comparatively short period of time.

Referring to the drawings:

Figure 1, is a side elevation, diagrammatic, of one half the length of a machine embodied in my invention, showing the loading and unloading end;

Fig. 2, is a similar view of the other half of the machine;

Fig. 3, is a diagrammatic view illustrating the air circulating system;

Fig. 4, is an enlarged vertical transverse section through the machine taken substantially on the line 4—4 of Fig. 1;

Fig. 5, is a section taken on the line 5—5 of Fig. 4;

Fig. 6, is an enlarged horizontal sectional view of the carrier-return end of the machine taken substantially on the line 6—6 of Fig. 7;

Fig. 7, is a vertical section taken substantially on the line 7—7 of Fig. 6;

Fig. 8, is an enlarged vertical sectional view showing in side elevation the air injector end, also referred to hereinafter as the stocking-exit end, of the drying compartment; and

Fig. 9, is a section taken substantially on the line 9—9 of Fig. 8.

The apparatus herein disclosed for performing the method above referred to is merely for purpose of illustration and other constructions might be employed and the several steps and operations varied without departing from the scope of the present invention.

The boards or forms designated generally by 15 which hold the knitted articles are preferably of aluminum, shaped to conform to the knitted shape of the articles or to any given shape which it is desired the articles shall conform to when finished. The forms are also preferably flat and tapered at their edges to a sharp but rounded edge. Each stocking will be drawn onto a form to a predetermined length and held at such length throughout the several operations by a suitable clamping or holding device including clamping elements 16 (Fig. 4). The fabric of each stocking will thus be held taut or slightly extended but without appreciable stretching, so that it will be uniformly presented throughout its area to the several finishing agencies. The particular stocking clamp shown comprises the subject matter of my companion application Serial No. 738,756, filed September 20, 1924.

65 The stocking forms are suitably attached

to an endless carrier designated generally by 17 which in the present instance comprises a pair of roller chains (Fig. 4) connected together by crossbars 18 which may serve to carry said forms. The carrier chains are trained over sprocket wheels 19 and 21 horizontally spaced apart and supported for rotation on a suitable frame structure. This provides upper and lower carrier runs or flights which are supported from end to end by suitable tracks 22 and 23, respectively, (Figs. 4 and 5). In this case the stocking forms extend outwardly from the carrier and are spaced apart at uniform intervals as indicated by the dotted line positions in Figs. 1 and 2 and are arranged in a common plane with the flat plane of the forms parallel with the line of travel of the carrier as clearly shown in Figs. 4 and 5. The purpose of this is to uniformly present the fabric at each side of a form to the action of the liquid treating devices, and the drying and other agencies, so that the action and effect of each will be the same on the fibres throughout the area of the entire fabric of each stocking. The carrier will be propelled by suitable mechanism (not shown), preferably continuously at a constant speed, in this in a clockwise direction viewing Figs. 1 and 2.

The frame supporting the endless carrier is at present composed of structural iron such as angle irons and suitable intermediate connections, braces, side walls and partitions which enclose and house the operating devices and provide the desired passages, conduits, compartments, etc. The frame and housing might obviously be of any suitable construction best adapted for the particular conditions at hand and the size of machine desired. For convenience in building this machine I employ upright angle iron frame members 24 spaced apart transversely as shown in Fig. 4 to define a comparatively narrow passage way between which the stocking forms travel and upon which the carrier tracks 22 and 23 are mounted. These upright frame members are also spaced apart lengthwise of the machine, in this instance approximately 10 feet apart defining between adjoining pairs of frame members a section, these sections being indicated in Figs. 1 and 2 by reference numerals 25 to 41 inclusive. The frame structure intermediate the uprights defining these sections may be suitable for the purposes for which such sections are devoted, and in the drawings I have therefore for purpose of simplicity and clarity shown only such transverse and longitudinal sections through the machine as are necessary for an understanding of the invention. The reference herein to sections is therefore simply for purpose of illustration and clarity and in no way a limitation on the scope of the invention.

Referring to Fig. 1 it will be observed that

above the sections 26, 27 and 28 I provide at each side of the carrier a platform 42 on which the operators stand for performing the operations of inspection, unloading and loading. 5 At these sections the forms are exposed and freely accessible, whereas at practically all other times the forms are carried within an enclosure of one form or another as will be presently apparent but to which access may be 10 had at convenient points for inspection of the different processing operations. The section 26 at the upper run of the carrier, may therefore be termed the loading station. The 15 stockings may be loaded onto the forms by operators stationed at both sides of the carrier, although the particular means and method employed for drawing the knitted articles onto the forms is not essential since the forms might be loaded when detached 20 from the carrier and after being loaded might be operatively connected thereto. It is important however in loading or boarding the stockings that they shall be drawn down onto the form a predetermined distance and held 25 at such position until removed from the form when completely finished. Any of various clamping or holding devices might be employed for this purpose, but preferably one such as described in my above-mentioned 30 companion application which will not obstruct the dye and other solutions from the fabric.

From the loading station the boarded stockings will be carried by the endless carrier through the end section 25 to the lower run and then to the left through the sections 26, 27, 28, etc., in succession. In these lower run sections the stockings will be subjected to different processing operations, such as singeing, wetting out, dyeing, developing, and soap and acid scroupe, as described in my parent application. These operations with the exception of singeing involve the application of various liquids and solutions to the 40 boarded stockings; and in so far as the present invention is concerned, these liquids may be applied in any manner, as by immersion of the boarded stockings in tanks or by spraying the liquids on to the boarded stockings. The 45 latter method is disclosed herein, Figs. 4 and 5, which show a single spray-delivering unit. This comprises spray nozzles 43 carried by a vertical header 44 located at each side of the stocking passage so that the stockings travel 50 between the sprays and are subjected to a spray bath from each side. The nozzles are preferably of a type which delivers a fishtail spray; and by properly arranging the nozzles a line-like spray will be delivered from top 55 to bottom of the stocking at each side thereof. A series of such spray-delivering units may be employed for each operation, if necessary, said units being spaced apart longitudinally 60 of the lower compartment 45 so that a time interval intervenes between spraying oper-

ations, permitting the applied solution to penetrate the fibres and allowing by successive spraying applications, the desired contents-saturation to be obtained in the fabric. The spray headers 44 may be connected to 70 supply pipes 46 to which the solution will be delivered under pressure and at the desired temperature by apparatus (not shown), each series of spray units being supplied by independent apparatus. The liquid drains into 75 a tank or sump 47 and through a pipe 48 to the pumping apparatus and is thus circulated. It will be manifest that the sides of the lower sections in which a spray is delivered will be 80 suitably enclosed so as to confine the solution and prevent loss. Suitable baffles are also interposed between adjoining sections as a means of further separating the different solutions. This phase of my invention, that is, the treatment by spraying, is claimed in 85 my parent application above mentioned.

Following the final spraying process the stockings will be carried through the end section 41 up onto the upper run and into a dryer which in the present machine extends from 90 the beginning of the upper run to the inspection station above mentioned located at the section 28. This dryer is in the form of a long narrow compartment formed between the uprights 24 by side walls 49 and a top 95 wall 51 of heat insulating material and a bottom wall 52. Within this compartment extending longitudinally thereof at each side of the stockings are heating pipes 53, at present supported directly on the side walls. 100 These heating pipes extend from the section 29 to the section 40 and may be supplied with a heating medium in any suitable manner to maintain the desired temperature in the dryer, although an additional temperature 105 control is provided as will be presently apparent. The stockings thus travel through this drying compartment 54 from the inlet end thereof at the beginning of the upper run to the outlet end at the inspection station. 110

In order to hasten the drying, carry off the moisture contents and to aid in shaping the stockings on the forms, I have provided an air circulating system which will now be described. Air circulation is produced by a 115 centrifugal fan or blower 55 (Figs. 3, 6 and 7) located in the present instance at one side of the dryer compartment with the intake opening 56 of the fan in communication with the dryer compartment. The fan discharges 120 through a conduit 57 into a conduit 58 beneath the dryer compartment and extending the full length thereof, the conduit 58 being separated by a partition 59 from the compartment 61 in which the lower run of the carrier travels, this compartment 61 constituting an air passage as will be presently described. The air discharged by the fan into the conduit 58 will flow lengthwise therein 125 as indicated by arrows in Fig. 3 and will be 130

discharged therefrom through air nozzles 62 (Fig. 9) into the dryer compartment in close proximity to and at each side of the stocking forms. At this end the conduit or passage 58 is divided into two laterally spaced passages 63, one at each side of the dryer compartment, which passages are turned at 64 and terminate in the air nozzles 62 abovementioned which discharge the air into the air dryer 10 compartment in the direction opposite to the travel of the stocking forms therein. Air will thus be delivered under pressure into the dryer compartment at the carrier outlet end thereof and will flow in the same direction the 15 full length of such compartment. Inasmuch as there is a 90° turn in the flow of air from the dryer compartment into the fan intake a slight pressure will be built up at this end which prevents air from being drawn into 20 the fan from the adjacent spraying compartment below, that is, from the lower compartment in the sections 40 and 41, although the only passage way between the spray compartment in the section 40 is between the 25 baffles 65.

In order to prevent saturation of the air a predetermined volume is constantly bled off or exhausted through a bleeder pipe 66 at the end of the conduit 58 remote from the fan. 30 This bleeder pipe discharges into the compartment or conduit 61 located immediately above the spray compartment and having a vent pipe 67 at its end nearest the fan. As a result of this construction a predetermined 35 volume of air will be continuously exhausted through the bleeder pipe 66 conduit 61 and vent pipe 67, thus keeping the moisture content in the air circulating system comparatively low and promoting drying efficiency. 40 The volume of air exhausted in this manner may be controlled by suitable means such as a butterfly valve 68 in the pipe 66. As a result of continuously exhausting a given percentage of the air in circulation, fresh air will be 45 drawn into the system by an injector action of the nozzles 62, the air inlet being between said nozzles. Thus a cool, comparatively dry fresh air is continuously drawn past the stockings as they emerge from the dryer, the 50 effect of which is beneficial in its final drying, and in cooling and contracting the stockings which will better adhere to the shape of the form. By reason of this method it will be apparent that the air is coolest at the end it 55 enters the drying compartment and is gradually raised in temperature as it approaches the end of the compartment at which the stockings enter in the moistened condition. Thus the greatest moisture content is carried 60 off at the end of the compartment at which the stockings enter and carry the greatest moisture, and, inversely, the dry stockings leave the dryer at a point at which the air has the lowest moisture content. The warm air 65 passing out through the compartment or con-

duit 61 draws off with it the steam and vapors rising from the spray compartments, thus greatly reducing the tendency for vapor to escape.

The stockings emerging from the dryer 70 will be inspected by operators at each side of the carrier and will then be removed from the forms and packed in boxes ready for shipping.

It is believed that the foregoing conveys 75 a clear understanding of the objects and principles of my invention which is herein illustrated simply in one embodiment as applied to certain operations in the finishing of knitted stockings. Applicant believes that 80 the present invention discloses broadly new methods and principles as applied to the finishing of fabric articles and therefore, that suitable constructions and a wide range of 85 mechanical equivalents may be employed in practice without departing from the spirit and scope of the invention as expressed in the appended claims, in which—

I claim:

1. In apparatus of the character described, 90 in combination, a drying compartment, a carrier for moving knitted articles lengthwise through said compartment, heating pipes at opposite sides of the knitted articles, a centrifugal fan the intake end of which 95 is in communication with the compartment at the carrier entrance end thereof, an air conduit leading from the discharge end of said fan to the carrier outlet end of said compartment, and nozzles located on opposite sides of 100 the knitted articles at the point at which they emerge from the outlet end of said compartment and arranged to discharge air from said conduit into the outlet end of said compartment past the stockings, whereby to produce 105 an injector action for drawing fresh air into the compartment past the stockings emerging therefrom.

2. In apparatus of the character described, 110 in combination, a drying compartment, a carrier for moving knitted articles lengthwise through said compartment, heating pipes at opposite sides of the knitted articles, a centrifugal fan the intake end of which is 115 in communication with the compartment at the carrier entrance end thereof, an air conduit leading from the discharge end of said fan to the carrier outlet end of said compartment, nozzles located on opposite sides of 120 the knitted articles at the point at which they emerge from the outlet end of said compartment and arranged to discharge air from said conduit into the outlet end of said compartment past the stockings, whereby to produce 125 an injector action for drawing fresh air into the compartment, and means for continuously exhausting a predetermined volume of air from said circulating system.
